UNITED STATES PATENT OFFICE

ALFRED C. GILBERT, OF HAMDEN, CONNECTICUT, ASSIGNOR TO THE A. C. GILBERT COMPANY, OF NEW HAVEN, CONNECTICUT, A CORPORATION OF MARYLAND

CONSTRUCTION TOY

Original application filed December 22, 1927, Serial No. 241,837. Divided and this application filed December 22, 1928. Serial No. 327,837.

This invention relates to construction toys having a plurality of detachable elements which are adapted for assembly with each other in a variety of ways to form various 5 toy models and mechanisms.

More particularly this invention relates to a novel form of cam structure, which is adapted for use in combination with other toy elements to form toys operable to simulate actual mechanical movements for the purpose of instruction and entertainment. A toy in which the novel form of cam structure of this invention may be used, is illustrated and described in detail in a copending 15 application, Serial No. 241,837, filed December 22, 1927, of which this application is a division.

One object of this invention is to provide a toy element for a construction toy which will 20 be adapted for use as a camming member, whereby toy mechanisms formed by a combination of elements of the construction toy will operate as desired by the user.

Another object of this invention is to provide 25 a cam element for a construction toy, which will be of such structure that parts thereof may be used for other purposes in combination with other toy elements.

To these and other ends, the invention consists 30 in the novel features and combinations of parts to be hereinafter described and claimed.

In the accompanying drawings:

Fig. 1 is a side elevation of a construction 35 toy model, embodying the features of this invention;

Fig. 2 is a section on line 2—2 of Fig. 1;

Fig. 3 is a top plan view of the upper structure of the model toy;

40 Fig. 4 is a section on line 4—4 of Fig. 3;

Fig. 5 is a section on line 5—5 of Fig. 3;

Fig. 6 is a section through the novel form of cam element, and its associated parts.

The particular model or device selected to 45 illustrate the novel features of this invention, comprises a structure composed of a plurality of toy elements assembled in such a manner as to simulate in form and operation a box-making machine. This toy, which

50 is more specifically described in the above

mentioned copending application, may be mounted upon a suitable base by any suitable means which pass through perforations in the supporting members of the toy.

End members, each comprising toy elements 13, form the supports and the main parts of the frame-work for the toy illustrated. The side plates are of sheet metal and are provided with foot portions 14. The supports 13 are provided with a plurality of 55 series of longitudinally and transversely spaced apart perforations, the spacing of which is according to a predetermined standard. To the foot portion 14 of each plate an angle toy element 15 is secured by means of 60 a bolt 16.

The supporting members are secured together in spaced apart relation by means of 65 perforated angle strips 17. Two of the strips 17 extend across the top and two across the bottom of the toy, firmly securing the supporting members together. The angle strips 17 are provided with spaced apart perforations, and are secured to the supporting members by means of bolts 18, which pass through 70 corresponding perforations in each part.

A perforated plate 19 extends across the toy between the supporting members 13, and is secured at each end thereof to the lower 75 pair of strips 17, by means of bolts 20, which pass through corresponding perforations in each part. An angle strip 21 also extends across the toy and is bolted to the lower strip 17 by bolts 22, which pass through corresponding perforations in each part.

80 Mounted upon this lower structure is an upper structure which is supported by uprights comprising perforated strips 23, to the upper ends of which are secured in spaced apart relation a pair of side plates 24 and 25. This upper structure is adapted to support a vertically slid able element 26, to which is secured one end of a lever 27, which is pivoted at 28 to the side plate 25. Toy elements 29 are secured to the other end of the lever 27 85 to simulate a counter-weight. A portion of the upper structure overhangs the lower structure.

90 Intermediate the ends of the lever 27 and adjacent its pivot 28 a cam follower 30 is 95 100

provided which, in this instance, comprises a short screw which passes through a perforation in the lever 27 and is secured thereto by a nut 31. The follower 30 projects inwardly substantially at right angles to the lever 27, toward and into a groove 32, provided in a toy camming element simulating a drum cam, which is disposed intermediate the plates 24 and 25. The toy camming element, by means of screw clamp bushings 33, is secured to a vertically disposed rotatable shaft 34, and comprises a cylindrical body having a cam groove 32, disposed about its periphery. In the present instance, the cylindrical body is formed by two identically formed cup-shaped members 35 and 36, each having a screw clamp bushing 33 disposed axially thereof and secured upon a bottom portion 37 of each. By the use of screw clamp bushings either member 35 or 36 may be moved axially upon its supporting shaft to adjust these members relatively to each other to vary the slot 32 formed therebetween.

The edge of the sides of each of the cup-shaped members 35 and 36, and at the open end thereof, is cut at an angle to the plane of the bottom 37 to form an axially directed camming edge. When the members 35 and 36 are positioned axially upon the shaft 34, with their open ends in spaced apart opposed relation, a cam slot 32 will be formed between the opposing edges thereof. The bottom portion 37 of the cup-shaped members, as illustrated in the drawings, is formed partly by the material of these members and partly by a disk 38, which is secured to the members by bolts 39. In this instance, the bushings 33 are permanently secured to the disks 38 by riveting over a portion thereof.

The shaft 34 extends downwardly and is journaled in a perforation in the strip 21. A clamp member 40 is secured to the lower end of shaft 34 and rests upon the upper surface of the strip 21, to retain the shaft against downward movement. A clamp member 41 is secured to the shaft below and engages the under-surface of the base portion 42 of an inverted U-shaped bracket 43, mounted between the uprights 23, to retain the shaft 34 against upward movement, the shaft 34 passing through a perforation provided in the base portion 42.

A gear 44 is secured to the shaft 34, the teeth of which mesh with a worm 45 secured to a horizontally disposed shaft 46. The shaft 46 extends between the end supporting members 13, and may be journaled in corresponding perforations therein or in corresponding perforations in short perforated strips 47, secured to these end members. A gear 48 is secured upon the shaft 46 at the end thereof, remote from the worm 45, and meshes with a pinion 49, secured upon another horizontally disposed shaft 50. The shaft 50 extends between the end members

13, being journaled in corresponding perforations therein. The outer end of the shaft 50 extends beyond one of the supporting members 13 and has a pulley 51 mounted thereon, which is adapted to receive a belt from any suitable power source, such as a toy electric motor, to be driven thereby.

Rotation of the pulley wheel 51, through shaft 50, pinion 49, gear 48, shaft 46, worm 45 and gear 44, will rotate shaft 34, whereby the toy camming element will be rotated. Rotation of the toy camming element will cause the cam follower 30, disposed within the slot 32, to act upon the lever 27 to raise or lower it, according to the control of the lever 27, due to its connection with the slideable member 26, raises or lowers the latter.

The lowering of the slideable member 26 lowers a plate member 52, secured to the lower end of said member into engagement with an opposing plate member 53, which is secured to the upper end of a slideable member 54, and forces it downwardly against the action of a spring 55. The spring 55, by being secured to a pivoted lever 56, which in turn is secured to the slideable member 54, tends to retain the plate member 53 in its upper position. As more fully described in the above mentioned co-pending application, the cooperating movements of the plate members 52 and 53 simulate the operations of corresponding parts of a box-forming machine.

The novel form of camming member described above is of such construction that it may be used as a toy element of a construction toy for other purposes than the specific use described above. By the use of such a camming member toy mechanisms or models formed by the combination of detachable toy elements may be made to simulate actual mechanical movements for instruction and entertainment.

While I have shown and described a preferred embodiment of my invention, it is to be understood that the same is not to be limited thereto in all of its details, but is capable of modification and variation which will lie within the spirit of the invention and the scope of the appended claims.

What I claim is:

1. A construction toy, comprising a plurality of separable elements, adapted for assembly in various forms of toys, two of said elements being spaced apart to form end members, other of said elements secured thereto to form a lower supporting frame, a vertically movable part supported by said lower frame, other of said elements mounted on said lower frame to form an upper frame, a vertically movable part supported by said upper frame in vertical alignment with said first mentioned movable part, and means to move one of said parts toward the other, com-

prising a rotatable camming member and a lever pivotally connected at one end of one of said movable parts, said lever being engaged and operated by said camming member to raise and lower the part connected thereto.

2. A construction toy, comprising a plurality of separable elements, adapted for assembly in various forms of toys, two of said elements being spaced apart to form end members, other of said elements secured thereto to form a lower supporting frame, a vertically movable part supported by said lower frame, other of said elements mounted on said lower frame to form an upper frame having a portion overhanging said lower frame, a vertically movable part supported by said overhanging portion of said upper frame in vertical alignment with said first mentioned movable part, and means to move one of said parts into engagement with the other part to move the same, comprising a rotatable camming member and a lever pivotally connected at one end to one of said movable parts, said lever being engaged and operated by said camming member to raise and lower the part connected thereto, and means to return the engaged part into its initial position.

3. A construction toy comprising a plurality of separable elements adapted for assembly in various forms of toys, a lower supporting frame, a vertically movable part supported by said lower frame, an upper frame, a vertically movable part supported by said upper frame in vertical alignment with said first mentioned movable part, and means to move one of said parts toward the other comprising a rotatable camming member, and a lever pivotally connected at one end to one of said movable parts, said lever being engaged and operated by said camming member to raise and lower the part connected thereto.

4. A construction toy comprising a plurality of separable elements adapted for assembly in various forms of toys, a lower supporting frame, a vertically movable part supported by said lower frame, an upper frame, a vertically movable part supported by said upper frame in vertical alignment with said first mentioned movable part, and means to move one of said vertical movable parts into engagement with the other to move the same, comprising a rotatable camming member, and a lever pivotally connected at one end to one of said movable parts, said lever being engaged and operated by said camming member to raise and lower the part connected thereto, and means to return the engaged part into its initial position.

5. A construction toy comprising a plurality of separable elements adapted for assembly in various forms of toys, a lower supporting frame, a vertically movable part

supported by said lower frame, an upper frame, a vertically movable part supported by said upper frame in vertical alignment with said first mentioned movable part, and a cam member comprising a pair of identically formed cup-shaped elements each having a substantially flat bottom, and a peripherally extending side wall disposed substantially at right angles to said bottom, said side wall extending axially from said bottom and having its free outer edge disposed at an angle to the plane of said bottom, said cup-shaped elements being mounted upon a shaft with the free outer edges thereof in spaced apart opposed relation to form a slot therebetween, and a lever pivotally connected at one end to one of said vertically movable parts, and means secured to said lever and entering the aforesaid slot whereby rotation of said cam member will raise and lower the vertically movable part to which said lever is connected.

In witness whereof, I have hereunto set my hand this 13th day of December, 1928.
